UNITED STATES PATENT OFFICE.

LEWIS L. CREAMER AND FRANK A. SPARKS, OF MILLVILLE, NEW JERSEY.

BOAT-DETACHING DEVICE.

SPECIFICATION forming part of Letters Patent No. 338,164, dated March 16, 1886.

Application filed September 15, 1885. Serial No. 177,192. (No model.)

To all whom it may concern:

Be it known that we, LEWIS L. CREAMER and FRANK A. SPARKS, both residents of Millville, in the county of Cumberland and State 5 of New Jersey, have invented certain new and useful Improvements in Boat-Detaching Devices; and we do hereby declare that the following is a full, clear, and exact description of the invention, which will enable others skilled 10 in the art to which it appertains to make and use the same, reference being had to the accompanying drawings, which form a part of this specification, and in which—

Figure 1 is a perspective view of our improved boat-detaching device, showing the same locked and connected with the davit-fall. Fig. 2 is a perspective view of our improved boat-detaching device, showing the same open and disconnected from the davit-fall. Fig. 3 20 is a longitudinal vertical sectional view showing the device connected with the davit-fall, and with dotted lines showing the position of the parts in the act of being disconnected when the boat touches the water. Fig. 4 is a 25 vertical transverse sectional view taken on the line *x x* in Fig. 3. Fig. 5 is an end view, and Fig. 6 is a view showing a boat connected with the davit-falls by our improved detaching device and in position for being lowered. 30 The same letters refer to the same parts in all the figures.

This invention relates to apparatus for detaching boats from the davit-falls of vessels, whereby they are suspended or supported 35 when not in use; and it has for its object to provide a device of this class which shall possess superior advantages in point of simplicity, durability, and general efficiency, and which shall insure the detachment of the boat with 40 absolute certainty at the moment it touches the water and begins to float.

With these ends in view the invention consists in the improved construction, arrangement, and combination of parts, which will be 45 hereinafter fully described, and particularly pointed out in the claims.

In the drawings hereto annexed, A designates the base or frame of our improved detaching device, which consists, mainly, of the 50 cheeks or side pieces, B B, and which is pro-

vided at the ends with lugs C C, having perforations D, to receive the bolts E, whereby the device may be secured to the boat, one being arranged at the bow and one at the stern, substantially as will be seen in Fig. 6 of the 55 drawings.

The side pieces or cheeks, B B, are connected by transverse bolts F and G, on the former of which is pivoted a hook or bell-crank lever, H, while on the latter is pivoted a latch-arm, 60 I, provided at its upper end, on the side facing the hook H, with a recess, J, adapted to receive and hold or retain the upturned point or nose K of the said hook, which fits in the upwardly-beveled or indented upper side, L, 65 of the said recess J. The upper end of the latch-arm I is provided with a laterally-extending arm, M, the object of which will be hereinafter more fully stated.

The cheeks or side pieces, B B, of the device are provided in rear of the pivoted latch-arm I with bearings for a transversely-sliding pin or bolt, N, which is provided between the said cheeks with a fixed annular ring or collar, O, which serves to limit the sliding motion of the pin or bolt N and to prevent its withdrawal from its bearings. The bottom of the frame A has a transverse groove or recess, P, in which is seated an upwardly-bulging spring, Q, which bears against the under side of the 80 ring or collar O, and serves by contact therewith to retain the pin or bolt N securely in any position to which it may be adjusted.

Upon the rear side of the latch-arm I, adjoining one of the side pieces of the frame, 85 and extending over less than one-half the width of the said latch-arm, is formed a heel or shoulder, R, which, when the said latch-arm is in a raised position, may rest upon the collar O of pin N, thereby supporting the said 90 latch-arm in its raised position. When the pin N is withdrawn, so as to withdraw the collar O from the shoulder R, the weight of the lateral extension or arm M of the latch-arm I will cause the latter to tilt over to the 95 position shown in Fig. 2 of the drawings.

As has been already stated, one of the detaching devices is to be secured at the bow and one at the stern of the boat. The inner ends of the trip pins or bolts N are to be pro- 100

- vided with perforations S, to which are secured the ends of a line, T, extending longitudinally throughout the length of the boat, and by pulling which at any intermediate point both of the said trip-pins may be simultaneously and instantaneously withdrawn, so as to disengage the collars O from the shoulders of the latch-arms and enabling the latter to be tripped, as will be presently described.
- 10 U U in Fig. 6 of the drawings designate the davit-falls, the ends of which are provided with swiveled links V V, which, when the detaching devices are open, as shown in Fig. 2 of the drawings, may be readily connected with the same by simply inserting them between the hooks H and the latch-arms I, striking their lower ends of extensions, and thus bringing their upper ends together to the position shown in Fig. 1 of the drawings.
- 15 The latch-pins N may now be pushed back under the shoulders R of the latch-arms, thus locking the latter in position and retaining the swivel-links of the davit-falls securely in the detaching devices. In this position the parts remain while the boat is suspended from the davits.
- 20 When the boat is to be lowered, the first thing to be done will be to withdraw the latch-pins N, so as to disengage their collars O from the shoulders of the latch-arms. This is accomplished by a single pull upon the line T, as already set forth. The weight of the boat will serve to hold the inclined point or nose of the hook H securely in engagement with
- 25 the beveled recess of the latch-arm as long as the davit-falls are kept taut, thus preventing the boat from being detached while it is being lowered; but the moment the boat floats in the water and the davit-falls consequently be-
- 30 come slack, the weight of the laterally-extending arms M of the latch-arms will trip the latter, thus releasing the hooks H and instantly releasing or detaching the boat from the davit-falls.
- 35 From the foregoing description, taken in connection with the drawings hereto annexed, the operation and advantages of this invention will be readily understood without requiring any extended explanation.
- 40 The general construction of the device is simple and inexpensive, and it may be manipulated at any time with ease and certainty.
- 45 The importance is well understood of causing a boat to become detached from the davit-falls the instant it floats upon the water, especially when the vessel from which it is lowered is under way, or when the sea is heavy, as otherwise it would be instantly swamped.
- 50 By this invention the trip-bolts, which lock the device securely when the boat is not in use, may be withdrawn before or while the boat is being lowered, and the detachment will then take place instantly and automatic-
- 55 ally, as well as with absolute certainty, at the

moment the boat begins to float, thus preventing its being dragged by the vessel and the danger of its being swamped.

In the practical manufacture of this invention it may be found desirable to make various minor changes in the construction and arrangement of details; and we would therefore have it understood that we do not limit ourselves to the precise construction and arrangement of parts herein shown and described, but reserve to ourselves the privilege of making all such changes and modifications as may be resorted to without departing from the spirit of our invention.

Having thus described our invention, we claim and desire to secure by Letters Patent of the United States—

1. In a device for detaching boats, the combination of a frame having cheeks or side pieces, the hook pivoted between the said side pieces and having an upturned or inclined point or nose, the pivoted latch-arm having a beveled recess adapted to receive and retain the point of the hook, and provided with a weight or arm, and having a heel or shoulder formed upon its rear side, and the trip pin or bolt arranged to slide transversely in suitable bearings in the side pieces of the frame, and having a ring or collar arranged between the said side pieces, all constructed, arranged, and operating substantially as and for the purpose set forth.

2. In a device for detaching boats, the combination of the frame, the hook having an upturned point or nose pivoted between the sides of said frame, the latch-arm having a beveled recess, a laterally-extending weight or arm, and a heel or shoulder formed on its rear side, the transversely-sliding trip pin or bolt having a ring or collar adapted to engage the said heel or shoulder, and an upwardly-bulging spring arranged in a transverse groove in the base of the frame and adapted to bear against the collar of the trip-bolt, and to retain the latter in any position to which it may be adjusted, substantially as and for the purpose herein shown and specified.

3. As an improvement in devices for detaching boats, the herein-described frames secured one at the bow and another at the stern of the boat, each provided with a pivoted hook having an upturned point or nose, a pivoted latch-arm having a beveled recess adapted to retain the said point or nose, a laterally-extending weight or arm, and a heel or shoulder, a transversely-sliding trip pin or bolt having an annular collar adapted to bear against the said heel or shoulder, and a detaining-spring arranged to bear against the collar of the trip-pin, in combination with a line extending longitudinally through the boat and connecting the inner ends of the trip pins or bolts, which may thereby be simultaneously withdrawn from engagement with the

heels or shoulders of the latch-arms, and the davit-falls having swiveled links attached to their ends for engagement with the detaching devices, all arranged and operating substantially as and for the purpose herein shown and specified.

In testimony that we claim the foregoing as

our own we have hereunto affixed our signatures in presence of two witnesses.

LEWIS L. CREAMER.
